US0D1109736S

(12) **United States Design Patent** (10) **Patent No.:** **US D1,109,736 S**
(45) **Date of Patent:** **** Jan. 20, 2026**

(54) **DISPLAY SCREEN**

(71) Applicant: **This is Luke Gray Ltd**, London (GB)

(72) Inventors: **Luke Gray**, London (GB); **Jose Enrique Cardona Rivera**, Caguas, PR (US)

(**) Term: **15 Years**

(21) Appl. No.: **35/522,862**

(22) Filed: **Sep. 27, 2024**

(80) **Hague Agreement Data**

Int. Filing Date: **Sep. 27, 2024**

Int. Reg. No.: **DM/241531**

Int. Reg. Date: **Sep. 27, 2024**

Int. Reg. Pub. Date: **Nov. 8, 2024**

(51) **LOC (15) Cl.** **14-02**

(52) **U.S. Cl.**
